(57) CLAIM

The ornamental design for a pet accessory, as shown and described herein.

DESCRIPTION

FIG. 1 is a perspective view of a pet accessory, showing my new invention.

FIG. 2 is a top view of FIG. 1.

FIG. 3 is a bottom view of FIG. 1.

FIG. 4 is a left side of FIG. 1, wherein the right side view is a mirror image of this view.

FIG. 5 is a front view of FIG. 1; and,

FIG. 6 is a rear view of FIG. 1.

The portions of the pet accessory shown in broken lines form no part of the claimed design.
